UNITED STATES PATENT OFFICE.

WALTER H. SPAHR, OF ST. LOUIS, MISSOURI.

DESIGN FOR AN ADVERTISING-CARD.

SPECIFICATION forming part of Design No. 20,663, dated April 7, 1891.

Application filed January 21, 1891. Serial No. 378,597. Term of patent 7 years.

To all whom it may concern:

Be it known that I, WALTER H. SPAHR, a citizen of the United States, residing at St. Louis, in the State of Missouri, have invented and produced a new and original Design for Cards; and I do declare the following to be a full, clear, and exact description of the same, reference being had to the accompanying drawing, forming a part thereof.

10 The leading feature of my design consists in a card having thereon the representation of a towel, napkin, or splasher and other ornamentation, as shown in the drawing. The card is rectangular in outline, and the towel-like ornamentation is also rectangular and is represented as having a fringed border knotted to the edge thereof and extends out nearly to the edge of the card. The central portion of the design is represented as being provided

15 with a panel within which is a pictorial

sketch or representation, as shown. Between the panel and the fringed border the design is represented as having loops of a ribbon around it, with bows at two of the corners.

In the drawing, which represents one side 25 of a card embodying my design, A' indicates the card; A, the towel-like ornamentation; B', a background for the same; B, the central picture; a a, the fringed border; b b, the ribbon-loops, and c c the bows at the corners. 30

Having thus described my invention, I claim—

A design for a card, substantially as herein shown and described.

In testimony whereof I affix my signature in 35 presence of two witnesses.

WALTER H. SPAHR.
